UNITED STATES PATENT OFFICE.

VICTOR H. SLINACK, OF PHILADELPHIA, PENNSYLVANIA.

WELSBACH OR OTHER INCANDESCENT BURNER.

SPECIFICATION forming part of Letters Patent No. 699,251, dated May 6, 1902.

Application filed November 14, 1901. Serial No. 82,175. (No model.)

To all whom it may concern:

Be it known that I, VICTOR H. SLINACK, a citizen of the United States, residing at Philadelphia, in the county of Philadelphia and 5 State of Pennsylvania, have invented a new and useful Improvement in Welsbach or other Incandescent Burners, of which the following is a specification.

In the class of burners referred to provision 10 is made for regulating the supply of gas and the supply of air, to the end that the burners may be used on mains whose pressures vary within wide limits—for instance, in the use of natural gas—without danger of their becoming 15 dismantled. Usually a needle-valve is interposed between the gas-valve and the Bunsen mixing-tube for reducing and regulating the gas-pressure. The best of these constructions are, however, all more or less 20 defective, chiefly because the parts being necessarily threaded the thread soon becomes stripped or worn, with the result that the needle-valve becomes wasteful of gas.

It is the principal object of my invention to 25 guard against this loss or waste.

Further objects are to simplify the general construction of the burner; to add to its attractiveness, and to make the burner more efficient as a whole.

30 The nature, characteristic features, and scope of the invention will be more clearly understood by reference to the following description, taken in connection with the accompanying drawings, forming a part hereof, in 35 which—

Figure 1 is a side elevational view of the burner constructed in accordance with my invention, illustrating a simple mantle-support holder. Fig. 2 is a central vertical sectional view of the same. Fig. 3 is a section on line 3-3 of Fig. 2, and Fig. 4 is a view similar to Fig. 1 with a gallery applied.

In the illustration herein given use is made 40 of a support or yoke *a*, served with annular openings at top and bottom for the reception of the various parts. The base or bottom of the yoke constitutes the lower part of a Bunsen mixing-tube and has apertures *b* for the ingress of air. *c* is a thimble or member, one

50 function of which is to connect said tube with the gas-valve. An apertured sleeve or air-shutter *d* is revolvably mounted between the

member *c* and the yoke and co-operates with the apertures *b* to admit more or less air to the burner in a manner well understood. The 55 member *c* is threaded to fit a correspondingly-threaded part of the Bunsen tube and has a central orifice *e*, which constitutes the seat for a needle-valve *f*, the shank of which extends in the direction of the burner. The yoke *a* is 60 provided with a boss or member *g*, which is exteriorly threaded and on its inside constitutes a shoulder, the purpose of which will be presently explained. The member *g* receives a milled collar *h*, by which the needle-valve 65 is adjusted and which has the spider *i* for supporting the shank of said valve. The adjustable parts are shown as being provided with screw-threads; but it is manifest that other common means of adjustment might be resorted to if expedient or desirable. The casting *j* or upper member of the Bunsen mixing-tube is shown as being somewhat enlarged at its base and fitted to turn with the member *g*, but capable of ready detachable 70 connection therewith, as well as from the burner-head *k*, into which it extends. Provision is made for removing the burner-head and applying the mantle-support holder shown in Figs. 1 and 2 and consisting of a 75 ring *l*, provided with a socketed member having a set-screw. As shown in Fig. 2, the ring is secured in position by mounting it on the top of the yoke or support and screwing the burner-head down upon it. This is an inexpensive way of providing a holder for the mantle-support; but the ordinary gallery-support *m* (shown in Fig. 4) may be employed by simply sleeving it over the burner-head. The jet or stream of gas when it reaches the 80 needle-valve is split up by the latter and caused to impinge on the shoulder formed by the inner wall of the boss or member *g*, which in turn still further acts to break the force of the jet, besides tending to perfect the mixture of gas and air by establishing counter 85 opposing currents. This is important, for the pressure of gas in mains often fluctuates, particularly, as before stated, in the case of natural gas, to the detriment of the life of 90 the mantle.

It will be obvious to those skilled in the art to which the invention appertains that modifications may be made in details without de-

parting from the spirit and scope of the same. Hence I do not limit myself to the precise construction and arrangement of parts hereinabove set forth, and illustrated in the accompanying drawings; but,

Having described the nature and objects of my invention, what I claim as new, and desire to secure by Letters Patent, is—

1. In an incandescent burner, the combination of a Bunsen mixing-tube having an internal annular shoulder, a member adapted for communication with a gas-supply connection and with said Bunsen mixing-tube and having a valve-seat that projects into the Bunsen mixing-tube, and a needle-valve superimposed in said Bunsen mixing-tube and adapted to said valve-seat and acting when open to direct the gas-jet against said shoulder, substantially as described.
2. In an incandescent burner, the combination of a Bunsen mixing-tube having an internal annular shoulder, a tubular member detachably fitted in said Bunsen mixing-tube arranged for attachment to a gas-supply connection and having a valve-seat, and a needle-valve superimposed in said Bunsen mixing-tube adapted to said valve-seat, and acting when open to direct the gas-jet against said shoulder, substantially as described.
3. In an incandescent burner, the combination of a Bunsen mixing-tube having an internal annular shoulder, a member detachably fitted in said Bunsen mixing-tube arranged for communication with a gas-supply connection and with said Bunsen mixing-

tube and having a valve-seat, a needle-valve superimposed in said Bunsen mixing-tube adapted to said valve-seat and acting when open to divert the gas-jet against said shoulder, and means for adjusting the supply of air, substantially as described.

4. In an incandescent burner, a Bunsen mixing-tube having its inner wall provided with an annular shoulder, and means for regulating the admission of gas to said tube and causing it to impinge on said shoulder, substantially as described.

5. In an incandescent burner, the combination of a Bunsen mixing-tube having an internal annular shoulder, a support the base of which constitutes the lower part of said Bunsen mixing-tube, a thimble threaded for attachment to said base and with a gas-supply connection and provided with a valve-seat that projects into the Bunsen mixing-tube, a needle-valve superimposed in said Bunsen mixing-tube adapted to said valve-seat and acting when open to divert the gas-current against said shoulder, and means revolvably mounted with reference to the support for controlling the admission of air to the Bunsen mixing-tube, substantially as described.

In testimony whereof I have hereunto signed my name in the presence of two subscribing witnesses.

VICTOR H. SLINACK.
